UNITED STATES PATENT OFFICE.

DANIEL M. PFAUTZ, OF GERMANTOWN, PENNSYLVANIA, ASSIGNOR OF
ONE-HALF TO WILLIAM H. TIGERMAN, OF PHILADELPHIA, PENN-
SYLVANIA.

SWIVEL-TRUCK FOR ELECTRICALLY-PROPELLED CARS.

No. 841,435.

Specification of Letters Patent.

Patented Jan. 15, 1907.

Application filed June 1, 1906. Serial No. 319,667.

To all whom it may concern:

Be it known that I, DANIEL M. PFAUTZ, a citizen of the United States, residing at Germantown, in the county of Philadelphia and State of Pennsylvania, have invented certain new and useful Improvements in Swivel-Trucks for Electrically-Propelled Cars, of which the following is a specification.

My invention has relation to that class of electrically-propelled cars adapted to be suspended from an elevated-railway structure; and in such connection it relates to a swivel-truck adapted to travel along on said structure and support the car in a suspended condition.

The principal objects of my invention are, first, to provide a simple and efficient swivel-truck for elevated-railway structures with suspended cars; second, to provide a swivel-truck with two superposed disks movably connected at their periphery with each other and at their vertical central axis, the lower disk supporting the car and the upper disk supporting the lower disk and car and the axles of the driving-wheels and motor; and, third, to provide a car with two trolleys united at their lower ends and with mechanism adapted to bring one or the other of the said trolleys into operative position as required.

The nature and scope of my present invention will be more fully understood from the following description, taken in connection with the accompanying drawings, forming part hereof, in which—

Figure 1 is a side elevational view of a car and a portion of the superstructure of an elevated-railway system, showing in side elevation swivel-trucks supporting the car and a double trolley and means for operating the same, embodying features of my present invention. Fig. 2 is an end elevational view of a car and a portion of the superstructure, showing in end elevation a swivel-truck supporting the car. Fig. 3 is a top plan view of the swivel-truck of the car. Fig. 4 is a front elevational view thereof, partly sectioned; and Fig. 5 is a vertical sectional view of the swivel mechanism of the truck, the motor, axles, and wheels thereof being removed.

Referring to the drawings, *a* represents a

column supporting a cross-girder *a*, to which are suitably secured longitudinal girders *b* and *b'*. To the lower inner flanges *b* and *b'* of the longitudinal girders *b* and *b'* are secured rails *b* and *b'*, over which the wheels *d* and *d'* of the swivel-truck *f* of a car *d* suspended therefrom travels, as will be herein-after more fully explained. To the cross-girder *a* is secured a bracket *c*, carrying a hood *c'*, within which the electric trolley-wire *c* is located. The car *d*, suspended from the truck *f*, is provided with rear and front platforms *d* and *d'* and dashboards *d* and *d'*, and within the same is arranged a metal framework, as indicated in dotted lines in Fig. 1. The axles *d* and *d'* of the swivel-truck *f* are carried by brackets *f* and *f'*, suitably secured to the under side of a disk *f*, which by means of a king pin or bolt *f* and *f'*, brackets *f*, disk *f*, and bolt *f* are connected with the metal framework *f* of the car-body *d*, as shown in Fig. 5 of the drawings. Below the disk *f* and centered on the king-pin *f* is arranged a second disk *f*, which by means of the bolts *f* is rigidly secured to the metal framework *f* of the car *d* and rests directly upon the roof *d* thereof. To the disks *f* are secured, preferably, the four brackets *f*, each carrying at the upper free end a roller *f*, engaging the upper disk *f* at or near the periphery thereof. These four brackets *f*, rollers *f*, and the king-pin *f* permit a certain movement of the car *d* and disk *f* in respect to the upper disk *f*, which is supported by the axles *d* and *d'* of the truck *f* and to sustain the weight of the car *d*. The movable connection between the upper disk *f* and lower disk *f* permits the truck *f* of the car to take to sharp curves with ease, in which instance the rollers *f* by rolling over the disk *f* will readily adjust the position occupied by the lower disk *f* and car *d* to the oblique position occupied by the upper disk *f* and truck *f*. On the roof *d* of the car *d* is located a bracket *e*, carrying two trolley-poles *e* and *e'*, to the shaft *e* of which an arm *e* is secured, which arm by means of a rod *e* is connected with a bell-crank lever *e*. By operating a rod *e*, connected with the bell-crank lever *e*, one or the other of the trolley-poles and their respective wheels may be

brought into and out of engagement with the trolley-wire *c*, as will be readily understood by reference to Fig. 1 of the drawings.

Having thus described the nature and objects of my invention, what I claim as new, and desire to secure by Letters Patent, is—

1. In an elevated-railway system, a car having on its roof a swivel-truck, comprising two superposed disks, the upper disk adapted to carry the axles and driving-wheels of the car, and the lower disk adapted to carry the car and having brackets surrounding the upper disk and carrying rollers engaging said upper disk, said brackets and rollers in conjunction with said upper disk adapted to support the lower disk and car, substantially as and for the purposes described.

2. In an elevated-railway system, a car having on its roof a swivel-truck, comprising two superposed disks, the upper disk adapted to carry the axles and driving-wheels of the car, the lower disk adapted to carry the car and having brackets surrounding the upper disk and carrying rollers engaging said upper disk, a king-pin passing through the car and both of said disks, said king-pin, brackets and rollers in conjunction with said

upper disk adapted to support the lower disk and car, substantially as and for the purposes described.

3. In an elevated-railway system, a car having on its roof a swivel-truck, comprising two superposed disks, the upper disk adapted to carry the axles, driving-wheels and motor of the car, and the lower disk having bolts and brackets carrying rollers, said bolts adapted to connect said lower disk with said car, and said brackets adapted to surround the upper disk and engage the same with its rollers, a king-pin passing through the car and said disks, said king-pin, brackets and rollers in conjunction with said upper disk and the bolts of the lower disk adapted to support said lower disk and car, substantially as and for the purposes described.

In testimony whereof I have hereunto set my signature, in the presence of two subscribing witnesses, this 29th day of May, A. D. 1906.

DANIEL M. PFAUTZ.
